TIME SWITCH

John E. McAllister, Cleveland, Ohio, assignor, by
mesne assignments, to Arthur J. Hudson, Cleve-
land, Ohio

Application November 7, 1934, Serial No. 751,858

16 Claims. (Cl. 200—39)

The present invention relates generally to time delaying mechanism and more particularly to a time switch for opening or closing one or a plurality of electric circuits after a predetermined time interval.

An object of the invention is the provision of a novel time delay actuating mechanism, more particularly a time switch, embodying improved features of construction and operation which will increase the control, reliability, and application thereof.

Another object of the invention is the provision of a novel time delay actuating mechanism for producing a desired operation after the elapse of a predetermined time interval in which an actuating shaft is periodically rotated intermittently through an escapement mechanism controlled by a clock-driven means.

The invention resides in certain novel features and details of construction and combinations and arrangements of parts, and further objects and advantages thereof will be apparent to those skilled in the art to which it pertains from the following description of the preferred embodiment thereof, described with reference to the accompanying drawings, in which:

Fig. 1 is a front plan view of a time switch embodying the present invention;

Fig. 2 is a section on the line 2—2 of Fig. 1 with the indicator turned to the position shown in dotted lines;

Fig. 3 is a section on the line 3—3 of Fig. 2, with the mechanism in the "off" position shown in Fig. 1;

Fig. 4 is a section on the line 4—4 of Fig. 2, with the mechanism in the "off" position;

Fig. 5 is a section on the line 5—5 of Fig. 2, with the mechanism in the "off" position;

Fig. 6 is a section on the line 6—6 of Fig. 2, with the mechanism in the "off" position; and

Fig. 7 is a schematic wiring diagram showing the device of Figs. 1 to 6 inclusive applied to a hair curling machine.

Similar reference characters designate corresponding parts throughout the several views of the drawings.

Briefly stated, the illustrated preferred embodiment of the invention, which is an electric time switch, comprises a spring actuated rotary switch operated through an escapement mechanism controlled from a rotatable shaft provided with a hand grasp for manual movement in opposite directions and adapted to be rotated in one direction by a clock mechanism. The hand grasp, which also serves as an indicator, is movable

through a predetermined arc, and the escapement mechanism is actuated to produce one-half rotation of the switch upon each complete oscillation of the hand grasp.

Movement of the hand grasp in a clockwise direction winds both the clock mechanism and the switch actuating spring, and as the indicator reaches or passes the mark 30 at the end of the scale, the present time switch being a thirty-minute switch, the escapement mechanism is actuated to rotate the switch a predetermined amount and close the same. The switch remains closed until the indicator is returned to the zero mark of the scale, either through manual operation or under the actuation of the clock mechanism, at which time the escapement mechanism is again actuated and the switch opened. In this respect the present invention differs from prior devices wherein the switch is actuated to close the circuit when the indicator is moved in a clockwise direction adjacent the beginning of the scale, and actuated to open the circuit when the indicator is returned to the zero mark. One of the advantages of this construction resides in the fact that the clock mechanism can be utilized to measure short intervals of duration, say up to twenty-five minutes in the present instance, without affecting the circuit, etc.

Referring to the drawings, the frame of the device illustrated comprises a base 10 of generally rectangular shape provided with a circular boss 11 formed integral therewith, a disc 12 supported in parallel spaced relation to the base 10 by a plurality of posts 13, 14, 15 and 16, and a disc 17 supported in parallel spaced relation to the disc 12 by a plurality of posts 18, 19, 20, 21 and 22. The posts may be secured to the base 10 and the discs 12 and 17 in any convenient manner, and any desired arrangement of the posts may be employed within limits which will be hereinafter apparent.

The switch proper is housed between the base 10 and the intermediate plate 12, and comprises a rotary switch element consisting of a plurality of plates 28 and 29 fixed to an escapement ratchet 45 or disc 30 by rivets 31 and insulated therefrom by insulation 32. The outer ends of the plates 28 and 29, which project on opposite sides of the composition ring-shaped member 33 are cut away, as is illustrated in the drawings, to form a plurality of blades, in the present instance four, designated as 34, 35, 36 and 37. As illustrated, the blades 34 and 35 are 45° apart, and the blades 36 and 37 are spaced 180° from blades 34 and 35, respectively. Upon rotation of the rotary switch 55

element, the blades 34, 35, 36 and 37 successively engage a plurality of stationary contacts 40 to 44 inclusive positioned in cutout portions 45 of the ring-shaped member 33. The stationary contacts are secured to the boss 11 by screws 46 and provided with electric connectors or terminal posts 47 formed integral with the contacts. Any arrangement of blades and contacts may be employed to meet the needs of a particular switching operation. The present embodiment is merely illustrative and a practical application thereof is hereinafter referred to.

The rotary switch element, consisting of the plates 28 and 29 and the escapement disc 30, which is provided with a downwardly extending boss 48, is rotatably supported on a central shaft 50 and rotated in a clockwise direction, as viewed in Figs. 3 and 4, by a helical spring 51 positioned about a collar member 52 rotatably supported on the upper end of the shaft 50. One end of the spring 51 is connected to a pin 53 secured to the escapement disc 30 and the other end to a pin 54 on a ratchet disc 55 riveted to the upper end of the collar member 52, which, as previously stated, is rotatably supported on the shaft 50. The shaft 50 is non-rotatably secured in the base 10 in any convenient manner, and, if desired, suitable means may be provided at the upper end of the shaft for retaining the collar member 52 in position thereon.

Rotation of the switch element under the action of the spring 51 is controlled by a bell-crank shaped escapement pawl 56 rotatably supported about a post 57 reduced opposite ends of which project through apertures in the intermediate plate 12 and a bracket 59 secured to the boss 11 by a screw 60. The post 57 is held in position by a nut 58 threaded on the upper end thereof. Opposite ends of the bell-crank escapement pawl 56 are adapted to project alternately into the path of movement of two upstanding stops or lugs 61 formed integral with the escapement disc 30 to permit an intermittent rotation of the rotary switch element in steps of 45°. The operation of the escapement pawl 56 is under the control of a small cam 63 secured to the squared end 64 of a central shaft 62 rotatably supported in the discs 12 and 17 through the medium of a forked or Y-shaped lever 65 formed integral with the escapement pawl 56 and rotatably supported on the upper end of the post 57.

The central shaft 62 is adapted to be oscillated through an arc of approximately 210° to 215° by a combination hand grasp and pointer 70 secured to the outer tapered end thereof by a flanged cap nut 71 rotatably supported in the hand grasp with the flange 72 positioned between a shoulder on the hand grasp proper and a tapered member 73 pressed into the hand grasp. The member 73 is secured on the tapered end of the shaft 62 by a forced fit and the construction permits the same to be readily secured to and removed from the taper for the purpose of assembly and adjustment of the pointer with reference to a scale 74 on a cover plate 75 spaced from the outer disc 17 and secured thereto in any convenient manner. A pair of positive stops 76 and 77, in the present instance secured to the outer disc 17 and projecting through the cover plate 74, are provided for limiting the movement of the combination hand grasp and pointer 70.

As the combination hand grasp and pointer is moved in a clockwise direction from the position shown in Fig. 1, which is referred to as the "off" position of the switch, the escapement pawl 56

is rocked from the position shown in full lines in Fig. 6 to that shown in dot-dash lines in the same figure, which latter position is reached as the pointer reaches or passes the mark 30 on the end of the scale, the present embodiment being a thirty minute time switch. The stop 61, in engagement with the leading end of the escapement pawl 56, is thereby permitted to advance 90° under the action of the spring 51, or until it engages with or is caught by the hook on the trailing end of the escapement pawl. The escapement disc 30 carries the switch plates 28 and 29 therewith, disengaging the blades 35 and 37 from the stationary contacts 40 and 42, respectively, and engaging the blades 34, 33 and 31 with the stationary contacts 41, 43 and 44, respectively. This position of the switch is hereinafter referred to as the "on" position. Upon movement of the combination hand grasp and pointer in the reverse direction, the stop 61 is released from the hook on the trailing end of the escapement pawl 56 as the pointer reaches or passes the zero mark on the scale, and the rotary switch element rotated another 90° or until the following stop 61 engages the leading end of the escapement pawl.

Rotation of the ratchet disc 55 in a direction to unwind the spring 51 is prevented by the engagement of a pawl 80 in one of a plurality of groups of ratchet teeth 82 formed in the periphery of the ratchet disc 55 and spaced 180° apart. The pawl 80 is rotatably supported on a reduced portion of the post 13 and is continuously urged in a clockwise direction, as viewed in Fig. 4, by a spring 81 one end of which engages in a notch in the pawl and the other end in an aperture in the disc 12. Upon each complete movement of the combination hand grasp and indicator 70 in a clockwise direction, as viewed in Fig. 1, the ratchet disc 55 is advanced approximately 180° by the engagement of a pawl 85 rotatably supported on a member 92 projecting from the under side of a segment 86 secured to the lower squared end of the shaft 62 with one of two abutments 87 and 88 projecting upwardly from the disc 55. The pawl 85 is continuously urged in a direction to engage the abutments 87 and 88 by a wire spring 89 secured to the rear side of the pawl 85 and a pin 89' projecting downwardly from the under side of the segment 86. Movement of the pawl 85 in a clockwise direction, as viewed in Fig. 4, is limited by a pin 94 carried thereby which engages one side of an elongated aperture 90 in the segment 86. The cam 63 previously referred to and the segment 86 are secured to the squared end of the shaft 62 by a nut 91 threaded on the lower end of the shaft. Suitable spacers 93 are positioned between the cam 63 and the segments 86 to properly locate the same.

Both ends of the segment 86 are provided with a plurality or group of ratchet teeth 100 adapted, as the combination hand grasp and pointer approaches the end of its movement in either direction, to be engaged by a double-faced pawl 101 rotatably supported on a reduced portion of the post 16. This construction prevents reverse movement of the hand grasp or pointer without the same having been moved through its complete arc in either direction. As the hand grasp reaches the end of its movement in either direction, the pawl 101 disengages the segment 86 and is held thereafter in a midposition by a spring 102 one end of which projects through an aperture in the pawl and the other end through 75

an aperture in the disc 12. This mechanism is referred to as the full wind mechanism and prevents the switch from being operated without the spring 51 being completely wound. When the hand grasp is moved in a clockwise direction a sufficient distance to actuate the rotary switch element, it cannot be reversed until the pawl 88 has engaged the next following groups of ratchet teeth 82 on the ratchet disc 55, and, when the hand grasp has been moved in the opposite direction far enough to open the switch, it cannot be reversed before the pawl 85 has been positioned for engagement with the next following abutment 87 or 88, as the case may be.

Upon movement of the combination hand grasp and pointer 70 in clockwise direction, the rotary switch element snaps or moves to the "on" position as the pointer reaches the end of the scale. When the time rotary switch element snaps to the "on" position, the full wind pawl 101 is in engagement with the ratchet teeth 100 at the lower end of the segment 86, as viewed in Fig. 4, and the rotary switch element will remain in this position indefinitely, that is, until the pointer 70 is manually moved sufficiently to allow the pawl 101 to clear the end of the segment. The foregoing construction permits the device to be used as a straight snap switch if desired.

Since after a predetermined movement of the hand grasp the same can only be turned in one direction, because of the engagement of the pawl 101 in the ratchet teeth 100 of the segment 86, visible means is provided for indicating the direction the hand grasp is to be moved. This means comprises a member 105 secured to the upper end of the small rod 106 welded or otherwise fixed to the pawl 101. The member 105 is provided with a plurality of arrows visible through a plurality of slots 107 and 108 in the cover plate 75.

The shaft 62 is adapted to be driven in a counter-clockwise direction, as viewed in Figs. 1, 2, and 4, by a clock spring 110 one end of which is secured to the post 111 and the other end to a collar member fixed to the large portion of the shaft 62 by a force fit. Movement of the shaft 62 under the action of the spring 110 is controlled by a clock mechanism of conventional construction designated in general by the reference character 113. The clock mechanism 113 includes a gear 114 rotatably supported coaxially with the shaft 62 and connected therewith through a friction drive, which drive consists in clamping the gear 114 between a spring washer 115 and the collar member 112. The amount of friction between the gear 114 and the member 112 is determined by the tension of the spring washer 115 which can be adjusted by a nut 116 threaded onto the shaft 62 and held in any adjusted position by a jam nut 117. The operation of the foregoing is such that, as the hand grasp is moved in a clockwise direction, the clock spring 110 will be wound, and when the hand grasp is turned manually in a reverse direction, the frictional drive between the collar member 112 and the gear 114 allows the shaft 62 to turn independently of the clock mechanism. The operating mechanism of the device is all enclosed in a metal case 119 open at the front to expose the dial, etc.

Fig. 7 is a schematic wiring diagram showing the present time switch applied to a hair waving machine. The stationary contacts 42 and 43 are connected to one side of the line, designated L₁,

the stationary contact 40 to an indicator lamp 120. The stationary contact 41 is connected to one side of the heater circuit 121 of the hair curler and the stationary contact 44 to one side of a voltmeter 122. The opposite sides of the indicator lamp 120, the heater circuit, and the voltmeter 122 are connected to the other side of the line, designated L₂. The switch is shown in full lines in what is herein referred to as the "off" position, and the dotted lines indicate the "on" position of the switch.

In the "off" position, the circuit to the indicator lamp is closed and a visible indication given that the switch is "off" or, in other words, that the circuit to the heaters is open. In the dotted line position the heater circuit 121 is connected to the stationary contact 43 and, in turn, the line through the blades 36 and 34, and the blade 37, is in contact with the stationary contact 44 to close the circuit to the voltmeter which then indicates the line voltage of the heating circuit.

From the foregoing description of the preferred embodiment of the invention, it is believed the operation thereof will be apparent, suffice it to say that as the combination hand grasp and indicator 70 is oscillated through its cycle of movement, the rotatable switch element is rotated in steps of 90° by the spring 51 through the escapement pawl 56. Upon oscillation of the hand grasp 70 in the clockwise direction, the ratchet disc 55 is rotated approximately 180° to wind the spring 51, preparatory to being unwound by the aforesaid rotation of the rotary switch element in two steps of 90° each. When the device is operated as a time switch, the hand grasp 70 is given a complete turn in the clockwise direction to wind the escapement spring 51, and turn the rotary switch element to the "on" position, after which the pointer is manually moved to the time setting desired. Continued movement of the pointer toward the zero end of the scale is effected by the clock mechanism, and, as the pointer reaches the zero mark, the rotary switch element advances 90° or to the "off" position. As has been previously stated, one of the advantages of applicant's construction resides in the fact that the device may also be used as a clock within certain limits without affecting the circuit or circuits to which it is connected, or may be used as a straight or regular snap switch if desired.

While the preferred embodiment of the invention has been illustrated as applied to a hair waving machine, it will be apparent to those skilled in the art that the invention is equally applicable to any circuit where it is desired to open or close the same after a time interval. It will also be apparent that numerous constructions of rotary contactors can be substituted for the rotary switch shown, and any desired arrangement of circuits, indicators, lamps, voltmeters, etc., obtained.

The invention resides in certain novel features and details of construction and combinations and arrangements of parts, and this application is intended to cover all variations, adaptations, and uses thereof that come within the knowledge and customary practice of those skilled in the art to which it pertains. I do not wish to be limited to the particular construction shown which may be varied within the scope of this invention, and I particularly point out and claim as my invention the following:

1. In a device of the character referred to, the combination of a rotary member, a second member rotatably supported coaxially with said first

- bers, a sector-shaped oscillatory member having spaced ratchet means thereon adjacent the ends thereof, means for oscillating said oscillatory member, a pawl adapted to engage the ratchet means on said oscillatory member for preventing reverse movement of said oscillatory member during a predetermined movement thereof, a one-way driving connection between said oscillatory member and said second member, and means operatively connected to said oscillatory member for controlling the rotation of said first member under the action of said spring.
12. In a device of the character referred to, the combination of a rotary member, a ratchet member having spaced ratchet means thereon rotatably supported coaxially with said first mentioned member, a pawl adapted to engage said ratchet means and limit the rotation thereof in one direction, a coil spring operatively connected to said rotary member and said ratchet member for rotating the latter, an oscillatory member, means for oscillating said oscillatory member, additional spaced ratchet means on said ratchet member, a pawl carried by said oscillatory member for engagement with said last mentioned spaced ratchet means, and means operatively connected to said oscillatory member for controlling the rotation of said first member under the action of said spring.
13. In a time switch of the character referred to, the combination of stationary contacts, a rotary switch member, a second member rotatably supported coaxially with said rotary switch member, means for limiting the rotation of said second member, a coil spring operatively connected to said rotary switch member and said second member, an oscillatory member, a clock mechanism for moving said oscillatory member in one direction, a one-way driving connection between said oscillatory member and said second member, and means operatively connected to said oscillatory member for controlling the rotation of said rotary switch member under the action of said spring.
14. In a time switch of the character referred to, the combination of stationary contacts, a rotary switch member, a ratchet member rotatably supported coaxially with said rotary switch member, a pawl adapted to engage said ratchet mem-
- ber for limiting the rotation thereof in one direction, a coil spring operatively connected to said rotary switch member and said ratchet member for rotating the former, an oscillatory member, clock mechanism for moving said oscillatory member in one direction, a pawl carried by said oscillatory member adapted to engage with said ratchet member, and means operatively connected to said oscillatory member for controlling the rotation of said rotary switch member under the action of said spring.
15. In a time switch of the character referred to, the combination of a plurality of stationary contacts, a rotary switch member, a ratchet member rotatably supported coaxially with said first mentioned member, spaced ratchet means on said ratchet member, a pawl adapted to engage said spaced ratchet means for limiting the rotation of said ratchet member in one direction, a coil spring operatively connected to said rotary switch member and said ratchet member for rotating the former, a shaft, a segment-shaped member fixed to said shaft, ratchet means on opposite ends of said segment-shaped member, means for oscillating said shaft, pawl means for preventing reverse rotation of said shaft after the same has been moved a predetermined distance in either direction, additional spaced ratchet means on said ratchet member, a pawl carried by said segment-shaped member adapted to engage said second ratchet means, escapement means for controlling the rotation of said rotary switch member, and means operatively connected to said shaft for controlling the operation of said escapement means.
16. In a device of the character referred to, the combination of a rotary member, a second member rotatably supported coaxially with said first mentioned member, means for limiting the rotation of said second member, resilient means for operatively connecting said first and second members, an oscillatory member, a one-way driving connection between said oscillatory member and said second member, and means operatively connected to said oscillatory member for controlling the rotation of said first mentioned member under the action of said resilient means.

JOHN E. McALLISTER.
